UNITED STATES PATENT OFFICE.

WILLIAM H. BOYES AND ERWIN F. VON WILMOWSKY, OF NEW YORK, N. Y.

SYSTEM OF RAILROADS AND APPLIANCES PERTAINING THERETO.

No. 867,007.

Specification of Letters Patent.

Patented Sept. 24, 1907.

Application filed July 23, 1900. Serial No. 24,586.

To all whom it may concern:

Be it known that we, WILLIAM H. BOYES and ERWIN F. VON WILMOWSKY, both of the city of New York, county of Kings, and state of New York, have invented 5 a new and useful System of Railroads, of which the following is a specification.

Our main object is to provide means to travel with increased speed and in a smooth, noiseless manner. For this purpose, we have devised what may be called an 10 autobalancing system of railroads; it is a true one-rail railroad, and consists preferably, of an elevated track-girder of special construction and a half-bisected car which is sub-divided into sections and fitted to ride on said girder.

15 Half-bisected cars, frequently described as "saddle cars", have been used before, but they were not subdivided and not autobalancing, *i. e.*, they did actually run on one rail, but only for short moments of time, because the slightest force such as a light side-wind or 20 a movement of the passengers would unbalance the car. To counteract this condition, so-called guide wheels were kept running on the sides of the track-structure on special rails at a higher and a lower level. These guide-wheels, therefore took away from such known 25 systems the character of a true "one-rail railroad". Such systems were in actual operation two-rail railroads. Our system uses too as well upper as lower guide-wheels, but in a different manner, substantially as safety wheels and to take up centrifugal strains on 30 sharp curves, so that ordinarily they may not touch the track at all. Further, the known one-rail railroads try to balance the car practically on one line, which obviously is impossible; they generally have a narrow rail, or have wheels supporting the car without lateral 35 freedom relatively to the supporting rail. Our system accomplishes a balancing on principles which are fundamental to two-rails systems. The supporting wheel, in the new system, has a broad, concave, soft face, preferably, and a convex track of greater width, and permits 40 lateral play of said wheel and said track, and also permits different side inclinations of said wheel.

The above peculiar shape of wheelface and track provides a centralizing influence, forcing the wheel always to return to the track-center or rather to oscillate around 45 the track center line describing a practically sinusoidal curve, as said influence is the stronger, the more the said wheel is away from the said centerline. The cause of this influence is the same as the deviation which a cone shows when placed on a horizontal table and 50 pushed in a direction vertical to its axis. The resulting deviation will be called herein "evolving effect" of an axle or wheel which is supported substantially in two areas revolving at different speeds (owing to the difference of their radii of rotation). This is in analogy to two-rail railroads. It, also, will be seen that in

the new system the center of the face of the supporting-wheel and the center of the track, is, practically, not used, but only the two sides. When it is preferred to use an iron wheel-face, the latter may consist of two conical halves separated or not by a small distance, and 60 the track may have a hyperbolic cross section, the central part of which may or may not be omitted.

The above smoothly acting centralizing influence with enough lateral play is a characteristic feature of the new system, and forms a contrast when the jarring 65 effect of climbing wheel-flanges in the known one-rail railroads is considered. And the absence of wheel-flanges in the new system is an advantage when compared with two-rail railroads, especially for extra high 70 speeds.

Another distinctive feature of the new system consists in the particular use of the guide-wheels. In a strong side-wind and on sharp curves said wheels are used as in systems known, but under ordinary conditions the lower guide-wheels which are essentially further 75 away from the track-structure than the upper ones, remain passive, and therefore are called herein "safety-wheels."

The upper guide-wheels, when the car "section" under consideration is centric to the track, have a clear- 80 ance from the track-structure of *e. g.* one inch, and are located not within the vertical transverse-plane containing the supporting axle, but in the middle between two adjoining planes of this kind, and they are fixed either to both ends of the section or only to the forward 85 end. In the latter case, the rear end of the section is fastened to the front end of the adjoining section in such way that a certain lateral play *e. g.* up to three inches each way is permitted against elastic lateral pressure. Now, the section is constructed in a truckless way, 90 which is feasible owing to its small weight, the length being nine feet. The expression "trucklessness" is meant to describe a section in which the axle bearings (except for the up-and-down motion resulting from the elastic elements by which said bearings support the 95 weight of the section) are practically stationary in relation to the car body, so that wheel and section move practically together in horizontal direction. Under such conditions, the upper guide-wheels are substantially relieved of lateral pressure and act as "true guide-wheels" when the supporting-wheel exceeds certain 100 limits in its lateral oscillations, while for the rest of the time they are passive. But they may be made to press against their rails at least with a slight insignificant pressure under all conditions only to keep them in motion.

As the section is supported in one point, or more correctly in two small areas located close together, it will be seen that the section can be made to turn by the adjoining section or by the guide-wheel concerned with 110

the greatest ease. When the section is so turned by one of the pair of upper guide-wheels located at its front ends, the supporting-wheel proceeds to run slightly diagonally across the track and thereby relieves the guide-wheel referred to. But when it is prevented from doing so by a strong side-wind or at sharp curves, it tends to do it and said guide-wheel is at least partially relieved. Guide-wheels so located and so used are called herein "relieved guide-wheels". An essential condition to this relieving of lateral pressure is lateral freedom to the supporting-wheel upon a broad track and location of the pair of guide-wheels ahead of the supporting wheel and practically at the level of its lowest point and a practically stiff connection between the bearings of the three wheels referred to.

10 The gravity center of the empty section may be *e. g.* six inches above the track. Owing to the weight of the motors, which are gearless, it would require undesirable complications to so locate the gravity center that the same is always below the track. But even when the section is empty and the gravity center relatively high, the section is supported in stable equilibrium owing to the width of the wheel-face and to eventual side-inclination. Besides, adjoining sections uphold each other, 25 and in extreme cases the lower guide-wheels, called safety-wheels, come into play.

20 In the foregoing, the novel and fundamental features of the new system have been described as seen on the working mechanism of a single car section. To make 30 said features operative within a train, the described monocyclic truckless sections are joined flexibly in pairs at the top of the saddle and at the car-roof for taking up the motor-and brake-reactions, which otherwise would tilt a monocyclic section. But this is done so, 35 that a lateral divergence or deviation of adjoining section-ends is permitted working against elastic lateral pressure of a spring or of a rubber cushion. The pairs of sections so formed are joined laterally in the same way just mentioned. To avoid placing the series of sections so as to form a zig-zag line, each two adjoining 40 sections may be provided with lateral spring-including buffers, of the kind which are used in two-rail railroads, but used in such way and located in such manner that there is no looseness, *i. e.* said buffers may be located 45 at the height of the track or at the same time at the roof and at the car floor. The bodies of the sections are joined besides, on their outside and on the saddle, by flexible canvas such as is used generally in vestibuled trains. Platforms and loose couplings are abolished in 50 the new system. The inside of the train or, as the same may be called as well, of the sectional car may form one continuous inclosed space, if so desired. The floors of adjoining sections are joined by overlapping iron plates, as is known from vestibuled trains in two-rail railroads.

55 At stations there is a platform on each side of the track. As switches for the system a substantial platform, is used movable upon two horizontal rails at right angles to the main track. This platform may be twenty feet long and support two pieces of regular girder fitting 60 exactly the gap in the main track or, when moved to the other position, fitting exactly the gap between the main track and the side track. One of said pieces is of a curvature of about one hundred feet radius.

65 The flexibility of the car, which may be so long as any train, or, as it may be expressed as well, the great

subdivision of momentum of the car has a special significance at speeds such as one hundred and fifty miles an hour, because jarring is prevented thereby, wear and tear of the track and of the motors and of the rolling stock generally, is reduced by said flexibility. 70 For the wheel-face, cotton duck or any other fibrous material may be used such as skins, hides, leather, with interposed rubber and gritty material. Perforated and corrugated thin-sheet iron plates, which keep away a little from the wheel-face, alternate with the fibrous plates referred to and hold the latter in place, a number of bolts penetrating and compressing both kinds of plates. That the wheel-face is concave, and that it is of soft material, is not essential to the system, so long as the rotating axle of the supporting wheel is supported 80 by two little areas only a small distance apart, and for so far said areas have a different radius of rotation whenever the car section concerned ceases to be centric to the track, in such way that a centralizing influence is exerted, as is well known in two-rail railroads 85 but is new in one-rail railroads.

In all the foregoing, the general features of the new system have been explained. One particular way, in which it is preferred to apply said features, has been shown in the drawings, which form an integral part of 90 the specification. We do not limit ourselves to the particular figures given in specification and drawings. Such figures and dimensions are given merely for the sake of illustration.

Figure 1 is a plan of a section and parts of the adjoining sections and of the track. It is understood that all sections are built exactly alike, except the front and the rear section which may be of somewhat pointed shape, and considering that generally only a few of the sections need to be provided with an electric current 95 collector. Fig. 2 is a longitudinal elevation of one section. Fig. 3 is a transverse elevation of one section. Fig. 4 is the same for a double-decked car. Fig. 5 is a longitudinal elevation of a double-decked car. Fig. 6 is a plan of a complete half-bisected sectional car upon a track shown while approaching a track switch, of which latter Fig. 7 is a side elevation. Fig. 8 is a diagram showing from above the relative zigzag position of two adjoining sections which is to be avoided by making the compressed buffer-springs, 100 referred to in the foregoing, of sufficient strength. There is generally a tendency to such zigzag formation, because—even when all sections have exactly the same motive power—each section tends to push the section in front, contributing thereby to overcome the head-air-resistance of the car. Fig. 9 is another diagram showing from above the relative position of a supporting wheel upon a track in a side wind, the wind being indicated by two small arrows. The wheel, as shown, is kept running slightly against the side wind by the right-hand guide-wheel shown, which latter presses hard on the guide rail while the left-hand guide-wheel is practically inactive. The rear guide-wheels of the same section (if there are any) are adjusted so, that they are further apart from each other, practically, 110 than the front guide-wheels. Fig. 10 represents the supporting wheel, its axle and two gearless electric motors and hoopbrakes with their upward reaching levers. Fig. 11 is a cut through the supporting wheel parallel to its sides showing one of the corrugated and 115

- perforated sheet-iron plates and the soft material beyond the same. Fig. 12 is a top view of a turnstile giving alternate access to the two platforms needed for a half-bisected car at stations. A permanent stationary 5 bolt (not shown) prevents the movable part of the turnstile to move through more than about a quarter of a circle. Fig. 13 is a vertical cut through one of the guidewheels of which each section in the drawings is shown to have four upper ones and four lower ones.
- 10 This cut shows a number of disks of soft material pressed together by bolts *i. e.* essentially the same construction as used for the supporting wheel. Fig. 14 the same seen from above. Fig. 15 is a diagram of an electric coupler between the gearless electric motor and a disk 15 attached to the axle of the supporting wheel, there being three coiled springs, of which only two are visible. Said disk has upon its periphery the hoop-brakes shown in Fig. 10. Fig. 16 is a bicyclic trolley device seen from above, which answers for speeds for 20 which a single trolley would be unsuitable. Fig. 17, the same, in vertical plane, but in a position corresponding to Fig. 16; *i. e.* a line which is horizontal in Fig. 17 is in reality a vertical line. Fig. 18 shows the application of the main features of our invention to a 25 track having two rails close together on which two wheels in close proximity are running. The lateral play is much greater than in two-rail railroads. No flanges are needed; the wheel-faces are large, as necessary for much lateral play. Fig. 19 is a cross-section 30 of the convex track rail and of the rim of the supporting wheel.
- The same symbols represent in the drawings identical or analogous parts.
- 1 is the track girder, which may be supported every 35 forty feet to form an elevated road; in which the car floor as well as the track girder have a clearance of the ground of about 12 feet. Or the girder may be supported on widely spaced sleepers close to the ground for interurban roads.
- 40 2 is the convex track consisting of short lengths of cast iron about five feet long and having a rough surface to afford sufficient grip to the soft wheelface; in respect to this grip, the well known experience of automobile rubber tires will serve as guide.
- 45 3 (Fig. 3) are rails for the upper guidewheels to run on. 4 are similar rails for the lower guidewheels. 5 are rails to supply power to the current collector.
- 6 (Fig. 2) (see below the left-hand central seat) is a 50 long casing including the long spring (48 in. Fig. 16). 7 is a casing containing the bicyclic trolley (Fig. 2). 8 is folded canvas between sections (Fig. 2) (see in the upper left hand corner of the drawing) on that part of the car where the roof slants down.
- 9 is a paneling (Fig. 2) on the lower half of the saddle. 55 10 is the car-floor. The gap in the same, between sections, is bridged over—besides the folded canvas mentioned in the above—by sliding iron plates.
- 11 are the sides of the car. 12 are the doors of the car.
- 60 13 is the folded canvas between sections. The same covers on the sides of the car a gap of four inches, measured when the car is on a straight track, and of eight inches, when measured while the car is on a curve of about one hundred feet radius, such measurement taking place on the outside of the curve.

14 (Fig. 2) is the framework or truck, the symbol 14 being marked on the main horizontal member of such truck of the motor-wheel.

15 is the saddle of the car, its top is flat, and 24 inches broad, and is reinforced at its ends and in the middle, *i. e.* at the points where the whole weight of the section is supported from the axle bearings of the motor-wheel with four intervening springs, 16, the latter being shown in elevation in Fig. 2 and in top view in Fig. 1.

17 (see Fig. 3 and 4) is the roof of the car.

18 (Fig. 1 and 2) is a cylindrical, vertical hollow space forming the center of the couplings which join each two neighboring sections, and which are located on the top of the saddle.

19 (Fig. 1 and 2) is the top of the saddle.

20 (Fig. 3) angle irons reinforcing the upper inside edges of the saddle.

21 (Fig. 1) are uprights of iron of suitable section forming the outside framework of the car.

22 (Fig. 2 and 3) is the upward reaching lever of the 85 hoop-brakes.

23 (Fig. 1, 2, 3, 5, 18, 19) is the face of the supporting wheel.

24 are the hubs of the supporting wheel. (Fig. 3).

25 see Fig. 3, forms the central part or web of the supporting wheel. The latter is shown to consist of two equal halves, divided in a medial plane.

26 (Fig. 19) is a metallic rim inclosing soft material, and fastened to the side of the wheel by the bolts shown.

27 (Fig. 19) are the corrugated thin sheet iron plates, 95 which hold back the soft fibrous plates, 28, against centrifugal strains, while all said plates are permeated by the bolts, 29.

30 (Fig. 1, 2, 4, 5) is the seat for the hoop-brakes.

31 is the bolt or axle around which the lever of the 100 hoop-brakes, 22 (Fig. 2) is made to turn.

32 (Fig. 2, 3, 4, 5) are the upper guide-wheel cases.

33 (Fig. 2) is the brake-rope, located at the very top of the car. It does not operate the lever, 22, directly; but through the medium of the coiled springs, 34. The 105 aim of this is to equalize the braking effect, and to make the same simultaneously acting on all the brakes of the train, respectively on all brakes on one side of the train.

35 (Fig. 3) are the rotating armature coils of the electric motor with which each half of the wheel is provided.

36 (Fig. 2 & 3) are the stationary field magnets of the motor wheel.

37 (Fig. 3) are sleeves supporting said magnets and 115 forming the axle bearings (Fig. 3) for the supporting axle, 39, to which latter the two hubs, 24, of the supporting wheel are fixed.

38 are the coils of the stationary field magnets (Fig. 3).

39 (see above after 37).

40 (Fig. 4) are tubes for supplying artificial ventilation and during the cold season heated air.

41 are the passenger seats.

42 & 43 (Fig. 4) are station platforms.

44 are the bicyclic trolley wheels held in the fulcrum, 45 (Fig. 3, 16 & 17).

46 (Fig. 15) are the three springs which form the elastic coupling between the motor (72) and the supporting axle.

75

80

90

95

120

125

130

47 are the bearings (Fig. 16 & 17) for the short trolley pole (65).

48 (Fig. 17, 16) is the long coiled trolley spring.

49 (Fig. 16) is the arm of the bicyclic trolley, which 5 is easily movable around its central pivot (66), so that when one wheel (44) is pushed off its rail (5) by a slight irregularity of the latter, its twin wheel (44) is pressed so much harder against said rail, insuring under all conditions good electrical contact.

10 50 (Fig. 3, Fig. 4) are the upper guide-wheels.

51 are the lower guide-wheels.

52 (Fig. 13) are the bolts within the guide wheels which compress the two sides and penetrate the plates of fibrous material.

15 53 are the cases of the lower guide wheels or safety wheels (Fig. 3).

54 (Fig. 1, 2, 5) is the casing for the supporting wheel.

55 (Fig. 2) is a flanged cylinder of vulcanized rubber of ample proportions, which is firmly compressed 20 between an outside metallic cylinder (57) and an inside one (56) by screwing down the strong washer plates, (58), on the screw thread with which 56 is provided on its upper end. 57 is fixed to the top of the saddle of the central section shown. 56 is fixed to 25 the saddle of the left-hand section of which only a part is shown.

59 (Fig. 2) are chains for holding adjoining sections together in extreme cases.

60 are ventilating tubes, the same as 40 (Fig. 3, 4).

30 61 (Fig. 5) are station indicators located in each section and consisting of a U-tube in which a colored liquid is made to ascend or descend by some electrical means with magnet and plunger or otherwise.

62 (Fig. 2) are transverse bars which join the lateral 35 wheel frames, 14.

63 is an upward projection of the latter frames.

64 (Fig. 3 & 16) are plates to which the bearings of the trolley device are fastened.

65 is the short pole of said device.

40 66 is the pivot of the latter.

67 are two pivoted braces joining the car-roofs (Fig. 1) of neighboring sections.

68 is a bar to support the motors. The latter are shown in Fig. 1 in two modifications. The central 45 section shown contains a motor wheel and the right-hand section shown contains a supporting wheel with separate motors.

69 are the armatures of the latter.

70 (Fig. 1 in the right hand section) are half elliptic 50 springs supporting the car section from the bearings, which latter are located between said motors and the supporting wheel.

71 are projections of which three are fastened to the disk of the hoop-brakes (Fig. 15).

55 72 represents the motor in Fig. 15, *i. e.* in the modification shown in the right-hand section of Fig. 1.

What we claim as our invention and desire to secure by Letters Patent of the United States is as follows:

1. A system of one-rail railroad which consists of a car 60 supported at the level of its gravity center by flangeless wheels of great width—such as the one-eighth part of the width of the car—and which consists besides of a track of greater width than the supporting wheels and permitting lateral play of said wheels—in combination with means to 65 allow varying side inclinations of said wheels and of the car; all for the purpose of supporting directly the gravity

center, which has a varying position relatively to the car owing to the different distribution of the passengers, and for the purpose of making independent from said inclinations the deviation of said center from the vertical plane 70 containing the track-center-line and for the further purpose of making allowance for the gyration effect by which an oscillation of a wheel around a vertical axis (resulting in said lateral play) is mutually accompanied by an oscillation around a horizontal axis (which results, in said 75 inclinations)—substantially as described.

2. In a one-rail railroad a half-bisected car, a track girder to support said car practically at the level of its center of gravity, broad-faced supporting wheels without flanges which—when the car is not centric on the track 80 touch the track in at least two points of different radii of rotation the lesser radius corresponding to the side to which it is desired to move the car for the purpose of centralizing—in combination with a suitable traction surface of a width sufficient to allow for the display of the 85 centralizing effect referred to.

3. In a one-rail railroad a girder provided with a wide convex traction surface, a half-bisected car, supporting wheels in said car with a running face adaptable to said convex traction surface and of a width smaller than this 90 surface and freely oscillating thereon for the purpose of keeping the car central to the track on straight or slightly curved stretches of the latter.

4. In a one-rail railroad a girder track provided with a wide convex traction surface, a half-bisected car riding on said track, supporting wheels in said car with a running face adaptable to the convex traction surface and of a width smaller than this surface for keeping the car centric on the track on straight or slightly curved stretches of the latter without the aid of guide wheels, and guide wheels 100 located between the supporting wheels at the level of the center of gravity of the car and with some clearance from the side of the girder and near the top of the girder so arranged as to give to the supporting wheel a direction slightly deviating from the exact direction of the track 105 and therefore to keep upon the track said supporting wheels on sharper curves of the track and when the car is exposed to a strong side wind—without the aid of any flanges of the supporting wheel—in combination with safety wheels running at the bottom of said girder.

5. In a one rail railroad for a half-bisected car supporting wheels oscillating upon a wider traction surface by virtue of the "evolving effect" in combination with guide wheels located between the supporting wheels and near the top of the track girder and relieved of lateral pressure 115 under ordinary conditions, but taking up the centrifugal stresses at the level of the center of gravity of the car when the car is rounding curves with considerable speed.

6. In a one-rail railroad a half-bisected car and a girder the sides of which have near the bottom and close to the 120 top rails for auxiliary wheels to run on, in combination with a broad flangeless supporting wheel and a broader supporting rail or their equivalents, the latter rail forming the top of said girder.

7. In a one-rail railroad a half bisected car and wide-faced supporting wheels, the rim of said wheels consisting of fibrous plates suitably secured, such as linen duck plates alternating with corrugated sheets of metal of smaller radius, in combination with a convex track of a width 125 surpassing the width of the wheel-face substantially as 130 described.

8. For a one-rail railroad a half-bisected car and wide-faced supporting wheels with yielding disks of fibrous material held between a number of thin metal plates and backed by elastic material in combination with a convex 135 track substantially as described.

9. In a one-rail railroad a sectional half-bisected car with subdivided motive power and constructed with such distribution of the building material that the gravity center is kept near the middle of the height of the car, and, therefore, near the level of the track, in combination with means to freely permit limited side inclination of each section of the car, the motion of the gravity center not being disturbed thereby.

10. In a one-rail railroad a sectional half-bisected car, 140 a single supporting wheel in the upper half of each sec-

- tion touching the track at the middle of the length—and of the width—and of the height of the section and means located between adjoining sections to mutually uphold the sections.
- 5 11. In a one-rail railroad a half-bisected car consisting of monocyclic sections in combination with uprights joining the saddle and the roof of the car and with close linking means located at two essentially different levels around said uprights substantially as described. 65
- 10 12. In a railroad a half-bisected car consisting of short sections, means to pivot each section at its geometric center and means to keep said center near the center line of the track in combination with other means to join the ends of the sections by a continuous flexible shell. 70
- 15 13. In a railroad a half-bisected car consisting of short sections, inside of the upper half of each section in the middle of its length a single supporting shaft the direction of which has a fixed relation to the car section in combination with gearless motors located around the shaft so arranged that the magnetic field lines are radial to said shaft and in combination with means—consisting in a suitable connection with the car skeleton—of keeping said shaft in alignment—and in combination with guide wheels which act as "true guide wheels" for the supporting wheels and at the same time as safety wheels for the section body, substantially as described. 75
- 20 14. In a railroad a half-bisected car consisting of short sections substantially without metallic contact between sections, close and at the same time elastic means of linking the sections together, supporting wheels with soft adaptable faces and soft faced guide wheels relieved of lateral pressure and means to pivot each section in combination with a track-supporting girder stiffened insides and possessing a smooth outside and reaching down to the car floor: all for the purpose of avoiding noises, vibrations and jarring. 80
- 25 15. In a railroad a sectional half-bisected car without platforms, individual doors on each side of said car, station platforms on each side of the track, means to afford alternating access to said station-platforms and an inclined step running along the edge of the station-platform, all for the purpose of avoiding the requirement of special attendants to secure an equal distribution of the passengers. 85
- 30 16. In a railroad a car, short sections forming parts of the car, flexible joints between the shells and of the sections, said shells and joints forming a smooth continuous inclosure, with uninterrupted inside space, close linking means between the frames of the sections near the highest and near the lowest point within the center plane of the car the whole car forming a vestibuled train without platforms and couplings. 90
- 35 17. In a railroad a car consisting of short sections, firm and elastic linking means between said sections, such as loose concentric metallic cylinders, allowing independent side inclinations, oscillations and vibrations of each section and suitable elastic elements, such as hollow substantial cylinders or elastic gums located between said metallic cylinders, for firmly opposing the motions referred 95
- 40 to preserving thereby the required rigidity of the car. 100
- 45 18. In a railroad a sectional car, flexible joints between sections in combination with a fin on top of the car of suitable height consisting of rigid pieces and of short flexible pieces at the section joints the fin being made of a height to locate the center of side wind pressure at some predetermined point and for the purpose to steady the general motion of the sectional car and damping the lateral oscillations of the individual sections. 105
- 50 19. In a railroad a sectional car, means to allow independent oscillations of each section around a vertical axis and around a horizontal axis parallel to the direction of travel in combination with means consisting in a suitable distribution of the weights—to change the radius of gyration concerned in said oscillations in some sections, for the purpose of avoiding the coincidence of the periods of oscillation of adjoining sections substantially as described. 110
- 55 20. In a railroad a car consisting of short sections—such as having a length of nine feet—, elastic linking means between sections, oblique section-ends joined by flexible material for enabling the car to round curves of the track. 80
- 60 21. In a railroad a half-bisected car consisting of short sections—such as of nine feet length—, suitable linking means between sections in combination with oblique section-ends and with flexible material joining the sections for the purpose of enabling the half-bisected car to turn around curves of the track which have a small radius. 85
- 65 22. In a railroad, a train consisting of a series of monocyclic units, each unit supported near its gravity center, at the lowest point of the supporting wheel, in combination with elastic means to restrain—by the neighboring sections—the various individual oscillations of each unit around a horizontal axis passing through said lowest point, and those around a vertical axis passing through the center of the wheel. 90
- 70 23. In a one-rail railroad for a half bisected car the combination of a supporting wheel and a pair of horizontal guide wheels, the latter located at the track-level and at the level of the center of gravity of the car and located at some distance ahead of the supporting wheel which they are guiding, for the purpose of relieving the guide-wheels of lateral pressure and of allowing the supporting wheels in a sidewind and at the curves of the track to keep in a direction slightly deviating from the direction of the track, in combination with a track the configuration of which allows a free play of the supporting wheels. 100
- 75 We have given in the foregoing a full and complete description of our invention. 105
- 80 In testimony whereof we have signed our names to this specification in the presence of two subscribing witnesses, this day 20 of July 1900. 110
